[57] CLAIM

The ornamental design for an automobile tire, as shown
and described.

DESCRIPTION

FIG. 1 is a perspective view of an automobile tire showing
my new design, it being understood that the tread
pattern is repeated throughout the circumference of the
tire;

FIG. 2 is an end elevational view thereof; and
FIG. 3 is a side elevational view of the side shown, the
opposite side being a mirror image thereof.

FIG. 1

FIG. 2

FIG. 3
